CLAIM

The ornamental design for a dog-waste-collection bowl, as shown and described.

DESCRIPTION

FIG. 1 is a top isometric view of the dog-waste-collection bowl;

FIG. 2 is a bottom rear view thereof;

FIG. 3 is a front view thereof, the rear view thereof being the same, the right view thereof being the same, and the left view thereof being the same;

FIG. 4 is a top view thereof; and,

FIG. 5 is a bottom view thereof.

Any shading and cross-hatching are not features of the design but are utilized to illustrate the surface contours of the dog-waste-collection bowl design in the drawings.

1 Claim, 5 Drawing Sheets
